UNITED STATES PATENT OFFICE.

DAVID COLE, OF EL PASO, TEXAS.

GRINDING MILL.

Application filed July 27, 1928. Serial No. 295,752.

This invention relates to grinding mills of the ball or rod type, and is designed particularly as an improvement on the structure disclosed and claimed in the patent to Cole and Bergman, No. 1,479,172, dated January 1, 1924.

The structure of the prior patent is characterized by the use of one or more riding rings supported on a plurality of rollers mounted on the pivot-pins of a chain structure suspended in arcuate form from its ends. One of the important characteristics of this structure is a stabilizing means which, without limiting the equalizing action of the chain, nevertheless restrains such motion toward the drum in a manner which has been found peculiarly effective to prevent rocking or cyclic oscillation of the drum in a direction transverse to its axis.

The present invention resides in structural details connected with the construction and mounting of the chain, by which the number of parts is greatly reduced and by which the drum is confined through its engagement with rollers mounted at the terminals of the pendant chain loop. In its simplest form, which is shown in the drawings, the drum is supported on two rollers supported between the ends of the chain structure, and is laterally confined by two rollers at the ends of the chain structure. These terminal rollers are so supported that the pull of the chain under load draws the confining rollers toward the riding ring of the drum. Adjustable limiting means are provided to control the motion of the terminal rollers toward the riding ring without restricting the outward motion. Thus the terminal or confining rollers do not positively limit the lateral movement of the drum but resist it, the follow-up motion of each roller being limited. In this way either roller is free to yield to impact and acts to absorb the energy of the impact without being free to exaggerate the rebound and thus tend to cause the drum to oscillate transversely.

Another feature of the invention is the mounting of the adjustable supports for the chain ends on a universal hinge so that they are self-aligning.

Still another feature is the arrangement of the parts so that both ends of the chain may be adjusted in the same direction and in the same or different degrees. This permits the axis of the drum to be alined with the axis

of the drive pinion, and to be adjusted toward and from the axis of the pinion to secure proper meshing of the pinion with the ring gear.

The preferred embodiment of the invention is illustrated in the accompanying drawings, in which

Figure 1 is a side elevation of a grinding mill embodying the invention, portions of the grinding drum being broken away to reduce the length of the figure;

Fig. 2 is an end elevation looking to the left relatively to Fig. 1;

Fig. 3 is a perspective view of the adjustable support for one end of one chain;

Fig. 4 is an elevation thereof.

In the structure chosen for illustration the drum is supported by two riding rings, one surrounding the intake throat and the other surrounding the discharge throat, these throats being at opposite ends of the drum. While this construction is preferred, certain features of the invention can be embodied in a structure having only one riding ring, and illustrated generally in Fig. 1 of the patent to Cole and Bergman, No. 1,479,173, also dated January 1, 1924.

Referring first to Figs. 1 and 2 of the present drawings, the mechanism is supported on suitable foundations which may be of concrete, the supports for the bearing structure for the drum being illustrated at 6 while the supports for the driving pinion shaft are illustrated at 7. Mounted on the supports 6 are hollow castings 8, said castings, viewed from the end of the drum, being formed with an arcuate depression producing at each end an upward projection or horn which terminates in a supporting plate 9 having a projecting lug 11. Mounted in the upper face of each plate 9 are two hemispherical bosses 12 which serve as fulcra for adjusting yokes indicated generally by the reference numeral 13. There are two such yokes on each horn, and each yoke includes a hub portion 14, an arm 15, and a stiffening web connecting the two. The lower face of the arm 15 at one end is recessed to fit upon the boss 12, and the other end is drilled to receive a bolt 16 which serves as a limit stop and is adjustable by means of a castellated nut 17 which, when adjusted, is pinned in place.

The two yokes 13 on each plate 11 are connected by a pivot-pin 18 which closely fits

in the hubs 14 at its ends, and which is locked in said hubs by means of the set-screws 19. The pivot-pin 18 carries a roller 21 which is a confining roller, and which is supported on said pin by means of anti-friction bearings of any suitable type (not shown). Also pivoted on the pin 18 are two links 22, one at either side of roller 21. These links are the terminal links of a chain structure pendant between the pins 18 on opposite horns of a single casting 8, and including in addition to links 22 the spacing links 23. The links 23 are pinned to the links 22 by journal pins 24 of ordinary form. 15 These pins carry journaled upon them between the two links 23 a pair of supporting rollers 25, preferably larger in diameter than rollers 21 but like these rollers supported on anti-friction bearings. 20 Supported on the rollers 25 and laterally confined by the rollers 21 is a corresponding riding ring 26, there being one riding ring 26 on the inlet neck 27 and another riding ring 26 on the discharge neck 28. These 25 necks 27 and 28 are shown as smaller in diameter than the body 29 of the drum but might be made of the same diameter; or to state the matter differently, the riding rings 26 might surround the body 29 of the drum. 30 Both arrangements are well-known in the art. The structure of the drum need not depart from standard practice, and as shown the drum consists of a plurality of sections connected by bolts passing through the mating flanges 31, 32. An encircling ring gear 33 is removably bolted to one of the flanges, preferably the middle flange, as is indicated at 34 in Fig. 2. The construction of the drum and the gear are not features of the 35 present invention. Mounted on the supports 7 in bearings 35 is a pinion shaft 36 which is driven by any suitable means, and which carries a pinion 37 which meshes with the ring gear 33 to rotate the drum. 40 Referring now to Fig. 4, A—B represents the center line of a link 22, and C—D represents the line of thrust between the hemispherical boss 12 and the axis of pin 18. The relation of the parts just mentioned is 45 such that the pull of link 22 tends to rotate the yoke 13 on the boss 12 in such direction as to carry the roller 21 toward the riding ring 26, the bolt 16 acting to limit this motion. By adjusting the nut 17 it becomes 50 possible so to position the rollers 21 that they seat firmly on the riding ring 26 but are incapable of moving further. Thus while the riding ring might act against the tension in a link 22 to force one of the rollers 21 back, 55 that is, away from the center of the drum, the other roller 21 could not follow up this motion. Consequently, while the guiding or confining rollers 21 are yieldingly mounted, they are incapable of setting up a transverse 60 oscillatory motion of the drum. 65

The universal mounting afforded by the use of the hemispherical bosses 12 renders the yoke 13 self-aligning, and permits the two yokes at the end of one pin 18 to be adjusted independently of each other to aline the pin 70 and consequently its carried roller, so that the roller bears fairly over the entire width of the riding ring.

The use of adjustable yokes 13 at both ends of the chain permits adjustable meshing of the gears by concurrent adjustment of the yokes. Where adjustable meshing of the gears is unnecessary or is secured by other means, only one end of the chain need have adjustable yokes. In such case as the 75 only purpose to be accomplished by the adjustment is the proper contact between the riding rings and the rollers 21, this can be secured by an adjustment at one end only.

It is necessary to provide some means to prevent the drum from oscillating longitudinally, that is, in the direction of its longitudinal axis. To accomplish this result economically and avoid troublesome adjustments, I provide on the interior of each casting 8 and opposite the middle of each link 23, a pocket whose semicircular form is indicated at 38 on Fig. 2, with a port or sprue 39 leading to the outer face of the casting. After the chain structures are mounted and 80 after the drum is at least approximately alined, bearing surfaces or bosses 41 of anti-friction metal are poured. These bosses engage the links 23 at or about their midlength 95 (see Fig. 1). In order to afford the proper degree of clearance, thin filler pieces of cardboard or the like may be inserted against the face of the link at the time of pouring the boss. This produces a very simple confining guide which may be readily replaced 100 when worn, or in the event that changed adjustment makes a differently dimensioned boss desirable.

For the sake of simplicity only two supporting rollers 25 are shown in the drawings 110 and this is the preferred construction, but it is to be understood that the invention is not restricted in this regard. In cases where very heavy loads are to be carried it may be found advisable to use a larger number. As the drawings are illustrative and not intended to be limiting, I do not confine myself to the particular embodiment shown but contemplate modifications within the scope of appended claims.

I claim:

1. Supporting and guiding means for the riding ring of a rotary drum comprising, in combination, a chain structure including two spaced series of links with pivot pins common to the two series and with rollers journaled on said pins and adapted to support and guide each riding ring; supports for the ends of the two link series those at at least one end of the chain structure includ- 125 130

- ing independently movable universally mounted members, whereby the members are rendered self-aligning; and independent adjusting means for said members.
- 5 2. Supporting and guiding means for the riding ring of a rotary drum comprising, in combination, a chain structure including two spaced series of links with pivot pins common to the two series and with rollers journaled on said pins and adapted to support and guide the riding ring; supports for the ends of the two link series those at at least one end of the chain structure including independently movable universally mounted members having a point of support below the end pivot pin and so offset relatively thereto that tension in the chain structure draws the end roller toward the ring; and means for adjusting said members.
- 10 3. Supporting and guiding means for the riding ring of a rotary drum comprising, in combination, a chain structure including two spaced series of links with pivot pins common to the two series and with rollers journaled on said pins and adapted to support and guide the riding ring; supports for the ends of the two link series those at at least one end of the chain structure including independently movable universally mounted members having a point of support below the end pivot pin and so offset relatively thereto that tension in the chain structure draws the end roller toward the ring; and adjustable means for limiting the motion of said members in a direction to carry the end roller toward the ring.
- 15 4. Supporting and guiding means for the riding ring of a rotary drum comprising, in combination, a chain structure including two spaced series of links with pivot pins common to the two series and with rollers journaled on said pins and adapted to support and guide each riding ring; supports for the ends of the two link series those at both ends of the chain structure including independently movable universally mounted members, whereby the members are rendered self-aligning; and independent adjusting means for said members.
- 20 5. Supporting and guiding means for the riding ring of a rotary drum comprising, in combination, a chain structure including two spaced series of links with pivot pins common to the two series and with rollers journaled on said pins and adapted to support and guide the riding ring; supports for the ends of the two link series those at both ends of the chain structure including independently movable universally mounted members having a point of support below the end pivot pin and so offset relatively thereto that tension in the chain structure draws the end roller toward the ring; and adjustable means for limiting the motion of said members in a direction to carry the end roller toward the ring.
- 25 6. Supporting and guiding means for the riding ring of a rotary drum comprising, in combination, a chain structure including two spaced series of links with pivot pins common to the two series and with rollers journaled on said pins and adapted to support and guide the riding ring; supports for the ends of the two link series those at both ends of the chain structure including independently movable universally mounted members having a point of support below the end pivot pin and so offset relatively thereto that tension in the chain structure draws the end roller toward the ring; and adjustable means for limiting the motion of said members in a direction to carry the end roller toward the ring.
- 30 7. The combination with a rotary drum having two riding rings, of chain structures for supporting said riding rings, each chain structure including two spaced series of links with pivot pins common to the two series and with ring-engaging rollers journaled on said pins; adjustable supports individual to each link series of each chain; and independent means for adjusting said supports.
- 35 8. The combination with a rotary drum having two riding rings, of chain structures for supporting said riding rings, each chain structure including two spaced series of links with pivot pins common to the two series and with ring-engaging rollers journaled on said pins; universally mounted supports, one for each end of each series of links, the parts being so arranged that the tension of the chain tends to carry said support and the terminal roller of the chain toward the riding ring; and adjustable means individual to each such support for limiting such motion.
- 40 9. The combination with a riding ring and a supporting chain structure carrying rollers pivoted on the chain structure and engaging the ring, of means for adjusting the alinement of the end rollers on said chain relatively to the axis of the drum.
- 45 10. Supporting and guiding means for the riding ring of a rotary drum comprising, in combination, a frame, two pivoted link structures with pivot pins common to the two and with rollers journaled on said pins and adapted to engage and support the ring; and renewable confining guides of anti-friction metal cast into pockets in said frame and engaging certain links of said structure.
- 50 60 members having a point of support below the end pivot pin and so offset relatively thereto that tension in the chain structure

draws the end roller toward the ring; and means for adjusting said members.

6. Supporting and guiding means for the riding ring of a rotary drum comprising, in combination, a chain structure including two spaced series of links with pivot pins common to the two series and with rollers journaled on said pins and adapted to support and guide the riding ring; supports for the ends of the two link series those at both ends of the chain structure including independently movable universally mounted members having a point of support below the end pivot pin and so offset relatively thereto that tension in the chain structure draws the end roller toward the ring; and adjustable means for limiting the motion of said members in a direction to carry the end roller toward the ring.

7. The combination with a rotary drum having two riding rings, of chain structures for supporting said riding rings, each chain structure including two spaced series of links with pivot pins common to the two series and with ring-engaging rollers journaled on said pins; adjustable supports individual to each link series of each chain; and independent means for adjusting said supports.

8. The combination with a rotary drum having two riding rings, of chain structures for supporting said riding rings, each chain structure including two spaced series of links with pivot pins common to the two series and with ring-engaging rollers journaled on said pins; universally mounted supports, one for each end of each series of links, the parts being so arranged that the tension of the chain tends to carry said support and the terminal roller of the chain toward the riding ring; and adjustable means individual to each such support for limiting such motion.

9. The combination with a riding ring and a supporting chain structure carrying rollers pivoted on the chain structure and engaging the ring, of means for adjusting the alinement of the end rollers on said chain relatively to the axis of the drum.

10. Supporting and guiding means for the riding ring of a rotary drum comprising, in combination, a frame, two pivoted link structures with pivot pins common to the two and with rollers journaled on said pins and adapted to engage and support the ring; and renewable confining guides of anti-friction metal cast into pockets in said frame and engaging certain links of said structure.

In testimony whereof I have signed my name to this specification.

DAVID COLE.
